Int. Cl. D24—02, 99

U.S. Cl. D24—1 D

FIG. 1 is a perspective view of the dental floss dispenser and applicator showing my new design;

FIG. 2 is a side elevational view looking from the rear in FIG. 1;

FIG. 3 is a top plan view looking down from the top of FIG. 2;

FIG. 4 is a bottom plan view looking up from the bottom of FIG. 2;

FIG. 5 is a front elevation view looking from the right of FIG. 2;

FIG. 6 is a rear elevation view looking from the left of FIG. 2; and

FIG. 7 is a perspective view of another embodiment of the dental floss dispenser and applicator.

The sides opposite FIG. 1 and FIG. 7 are mirror images to that shown.

The broken lines representing the dental floss are shown for illustrative purposes only.

I claim:

The ornamental design for a dental floss dispenser and applicator, as shown and described.
